(No Model.)

C. C. STEWART.

HOISTING DEVICE.

No. 351,293.

Patented Oct. 19, 1886.

UNITED STATES PATENT OFFICE.

CHARLES C. STEWART, OF ONEONTA, NEW YORK.

HOISTING DEVICE.

SPECIFICATION forming part of Letters Patent No. 351,293, dated October 19, 1886.

Application filed June 17, 1886. Serial No. 205,430. (No model.)

To all whom it may concern:

Be it known that I, CHARLES C. STEWART, a citizen of the United States, residing at Oneonta, in the county of Otsego and State of New York, have invented certain new and useful Improvements in Hoisting Devices, of which the following is a full, clear, and exact description, reference being had to the accompanying drawings, forming part of this specification, in which—

Figure 1 represents a sectional view of my device applied to the running-gear of a vehicle. Fig. 2 is a side elevation of my improvement with a portion of the frame broken away to show the mechanism for operating the brake. Fig. 3 is a detail of the ratchet-bar.

My invention relates to devices attached to the rear axle of a wheeled vehicle, and adapted to be used in removing heavy substances—such as rocks, logs, &c.—from a field, and for such other purposes as would necessitate the employment of a powerful lifting apparatus; and my invention consists in the construction and combination of devices hereinafter described, and specifically pointed out in the claims.

To enable others skilled in the art to which my invention appertains, I will now describe the manner in which I have carried it out.

In the said drawings, A represents the two sides of a suitable frame or casting, which is designed to be bolted or otherwise secured to the rear axle of a vehicle, and this casting is provided with grooves *a*, in which is vertically guided a rack-bar, B, the purpose and construction of which will be hereinafter developed.

An operating-lever, C, pivoted between the sides A of the main casting, has its inner end or short arm, C', bifurcated to receive a pivotally-mounted movable pawl, D, which engages the teeth on the rack-bar and elevates the latter.

Immediately above the pawl D, and mounted between the sides of the main frame or casting, is a second pawl, E, which I prefer to designate a "stationary" pawl, in that it holds the rack-bar in its adjusted position until changed by the future movements of the operating-lever and movable pawl D. The pawls D and E are provided with eyes *b* *c*, in which one end of suitable connecting-rods, *d* and *e*, is

secured, the outer ends of said rods being attached to eyes *f* and *g*, formed in bent levers F F', the short arms of which are pivotally secured to the opposite sides of the main or operating lever C, whereby the weight of the levers holds the pawls to their engagement with the rack.

From this arrangement of the several parts it is manifest the operator, by drawing upon the levers F or F', withdraws either or both the pawls D and E from their engagement with the teeth on the rack-bar, and permits said bar to drop or be lowered, as hereinafter set forth.

As before described, the rack-bar B has a vertical movement between the sides of the main casting, it being provided with tongues *h*, which fit within the grooves *a*. Upon the lower portion of the rack-bar is formed a cavity or groove G, and between the sides A is journaled a dog, H, provided with a grooved face, *l*, and projections *m* and *n*. Against the face of the latter a spring, *p*, secured to the rack-bar B, is designed to bear to throw the upper end of the dog H inward.

A loosely-placed roller, L, is introduced between the sides of the main frame, and when the rack-bar is being adjusted is designed to lie within the grooved face of the dog H; but when the rack-bar has been adjusted, by the repeated movements of the operating-lever, to bring the cavity or groove G into alignment with the grooved face of the dog H, the loose roller immediately falls into said cavity, and is retained therein by the action of the spring *p*, and keeps the rack-bar in a locked position until the roller is withdrawn from the said cavity or groove. To accomplish this latter result, I pivot upon the lower end of the short arm C' of the lever C a downwardly-projecting dog, M, adapted to come in contact with the lug *m* on the dog H, when the operating-lever is depressed, and force the upper end of the dog H away from the rack-bar, thereby enabling the loose roller to fall from its seat in the cavity in said rack-bar into the grooved face of the dog H, and permitting the rack-bar to be lowered by withdrawing the pawls D and E in the manner previously described.

The operating-lever B is provided upon its sides with eccentrics M', over which are placed one end of the arms N, the opposite end of

said arms being threaded, as shown at *r*, Fig. 2. These threaded ends pass through the rear of main frame A, and through a suitable brake-block, O, to which they are secured by suitable nuts and washers. A spring passes through the brake-block, and with its ends bearing against the back of the rack-bar. It is evident from this description that the movements of the operating-lever cause the eccentrics to 10 actuate the arms N, either to draw them against the back of the rack-bar or force them away from the same, thereby constituting a brake which assists in holding the rack-bar in its adjusted position. The rack-bar is provided 15 with a lug, *s*, which is designed as a stop to prevent the said bar dropping entirely out of the main frame, and the frame has projections *t*, which support the brake-bar.

Upon the lower end of the rack-bar is cast 20 or otherwise secured a plate, P, having a series of oblong perforations, U, which are designed to receive and support the upper ends of suitable grappling-hooks, R, whose lower ends are adapted to engage and hold the article 25 to be removed. The outer ends of the plate P terminate in hooks *P'*, over which suitable chains are passed when the device is employed for transporting heavy timbers, in which event the hooks are dispensed with, the chains being 30 passed around the timber in any secure manner. It is now manifest if the grappling-hooks and chains, when necessary, are made to engage the rock, log, or other object to be removed, and power applied to the operating lever, the rack-bar, and with it the article held 35 by the hooks, will be elevated above the ground a distance sufficient to enable the operator to drive to a remote part of the field, or any other appropriate place, and deposit said article by 40 withdrawing the pawls C and D and forcing the dog H from the rack-bar.

Having thus described my invention, what I claim as new, and desire to secure by Letters Patent, is—

1. In a hoisting device, the main frame, the 45 rack-bar sliding therein, and the pawls C and D and operating-levers, in combination with the brake-bar and eccentrics on the main lever, substantially as herein described.

2. In a hoisting device, the combination, 50 with a frame, a rack-bar, and operating-lever, of a brake-bar, suitable eccentrics on the operating-lever, and the arms N, engaging the eccentrics, whereby the brake-bar is operated, substantially as herein described.

3. In a hoisting device, the combination, 55 with a frame, a rack-bar sliding therein, and a lever having eccentrics upon its sides, of the arms N, engaging the eccentrics and provided with threaded ends, a brake-bar through which 60 the threaded ends pass, securing-nuts for the arms, and a spring, the ends of which bear against the back of the rack-bar, substantially as herein described.

4. In a hoisting device, a frame, a rack-bar 65 sliding therein, and an operating-lever, in combination with a dog, H, pivoted between the sides of the frame, a roller loosely supported in the end of said dog, and a second dog, M, pivoted in the short arm of the lever and 70 adapted to engage a projection on the dog H, substantially as herein described.

5. In a hoisting device, a frame, a rack-bar sliding therein and provided with a groove or cavity, in combination with a dog, M, pivoted 75 to the short arm of the lever, a dog, H, pivoted between the sides of the frame, a loosely-mounted roller seated in the face of the dog H and adapted to enter the groove or cavity in the bar, and a spring bearing against the 80 lower end of the dog H, substantially as herein described.

CHARLES C. STEWART.
